UNITED STATES PATENT OFFICE.

EDWARD G. SHORTT, OF CARTHAGE, NEW YORK, ASSIGNOR OF ONE-HALF TO M. CLINTON MASON, OF ROCKVILLE, CONNECTICUT.

CARBURETER.

1,133,754.

Specification of Letters Patent. Patented Mar. 30, 1915.

Application filed November 27, 1912. Serial No. 733,901.

To all whom it may concern:

Be it known that I, EDWARD G. SHORTT, a citizen of the United States, residing at Carthage, in the county of Jefferson and State of New York, have invented certain new and useful Improvements in Carbureters; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in carbureters, etc., the object in view being to afford means whereby a supply of fuel and air, properly proportioned may be quickly introduced into a combustion chamber, by manually operated mechanism whereby the effect may be produced similar to that obtained by the throttle valve of a locomotive.

The invention consists more specifically in the provision of a device of this character, in which means is provided for regulating the air passageway leading into a chambered coupling adapted to communicate with a combustion chamber, synchronously with the actuation of a fuel retarding device.

Another and essential object of the invention consists in the provision of means whereby the diameter of the passageway, through which the air and fuel pass to the engine, may be increased or decreased by the movement of the lever-operated valve, thereby causing a variable passage for the inrushing air.

Another feature of the invention consists of means whereby, when the supply of fuel is cut off when it may be desired to allow the engine to operate while coasting, air may be drawn into the combustion chamber for the purpose of cooling the same without allowing any fuel to be drawn into the combustion chamber.

The invention consists further in the provision of a controlling device adapted to engines of various capacities, and so operated as to prevent back fire reaching the fuel supply and effectually sealing the fuel when the device is not in use.

The invention comprises various details

of construction, combinations and arrangements of parts as will be hereinafter more fully described, shown in the accompanying drawings and then specifically defined in the appended claims.

I illustrate the invention in the accompanying drawings, which with the letters of reference marked thereon, form a part of this application, and in which:—

Figure 1 is a central longitudinal sectional view through the device. Fig. 2 is a sectional view taken on line 2—2 of Fig. 1. Fig. 3 is a sectional view taken on line 3—3 of Fig. 2. Fig. 4 is a side elevation. Fig. 5 is a top plan view. Fig. 6 is an end view, and Fig. 7 is a sectional view taken on line 7—7 of Fig. 1.

Reference now being had to the details of the drawings by letter, A designates a suitable casing containing the operative parts of the apparatus, and to which casing a flanged coupling member B is fastened by screws B' or other suitable fastening means. Said member has a threaded opening for the reception of a pipe, not shown, affording a means of communication between the casing and a combustion chamber.

A portion of one side of the casing is hinged as at C, affording a convenient means whereby access may be had to the interior thereof when desired for any purpose, and both the hinged portion of the casing and the opposite side wall of the latter, are provided with openings D for the admission of air to be supplied, suitably mixed with fuel, to the engine. The main chambered portion of the casing forms a variable air passageway, communicating through an opening E, with the interior of said coupling member B. Said opening, it will be noted, is slightly contracted and has a beveled valve seat E' formed in the marginal edge thereof, and through which seat a fuel duct F passes. Cast integral with the casing are the spider arms G radiating from a central bearing G'.

A valve stem H is mounted to have a longitudinal movement in said bearing and in an aperture formed in the end of the casing and at one end of the stem is a valve I with a beveled circumference and provided for the purpose of controlling the passage of air and fuel, properly proportioned, through the inlet opening communicating with the interior of the coupling member B.

Upon reference to Fig. 1 of the drawings, it will be noted that the inner surface of the wall of the coupling member B is inclined or tapering as at B², adjacent to the end of the casing to which said coupling member is fastened, and which tapering portion is disposed at an angle to the valve seat E' and this particular tapering portion of the coupling member, co-operating with the valve, forms a very essential feature of the present invention, in that the diameter of the passageway controlled by the valve I may be increased or decreased gradually, accordingly as the valve is moved from or toward its seat, thereby forming means whereby the velocity of the inrushing air may be maintained at nearly a uniform speed regardless of the speed of the engine. By the provision of this gradually increasing diameter of the passageway, as the valve is unseated, the vacuum drawing upon the fuel and air is maintained in order to properly feed the air and gas to the combustion chamber.

The end of the valve stem is provided with a threaded opening I' for the reception of the threaded shank portion of the screw I², the head of which is of greater diameter than the projecting end of the valve stem in which said threaded hole is formed, and a coiled spring I³ is interposed between said head and a disk valve I⁴, which latter is normally held by the spring I³ against the outer face of the valve I and normally closes the apertures I⁵ formed in said valve. The provision of said disk valve is to allow air to pass through the apertures I⁵ when there is a tendency for the disk valve to be drawn away from the face of the valve by suction force in the event of a vehicle coasting down a grade and when the valve is seated to shut off the supply of fuel, the air which may pass through the apertures I⁵ being utilized for the purpose of cooling off the engine.

Mounted loosely upon said valve stem is a resistance block K having lateral projections L and M, the former of which has a series of rack teeth N thereon, in mesh with the teeth O of the lever P, which latter is pivotally mounted upon a pin Q. Said lever, mounted as shown and described, forms means for moving the resistance block against the tension of the master coiled spring R which latter, at one end fits over the projecting portion of the bearing supported by said spider arms, and its other end extends over one end of a cylindrical portion of said resistance block, the purpose of said spring being to normally hold the valve seated.

Fixed to the valve stem is a flanged collar R⁴ against one end of which one end of the resistance block is held by said spring R when the valve is seated. A second coiled

spring R' is fitted over said collar and bears against the flange at the end thereof, and also over a second flanged collar R² which is loosely mounted on the valve stem. Said spring R', is much lighter than the spring R, and is normally held under tension by the latter.

Referring to Fig. 1 of the drawings, it will be seen that the oil duct F communicates with a slightly tapering aperture J formed longitudinally in the threaded spray bushing J' which is fitted in a hole having a threaded wall. The projection M of the resistance block is split and is provided with threaded jaws for the reception of the threaded shank S of the retarding member S'. Said jaws are held in proper adjusted positions relative to the threaded portion of the shank, through the medium of a set screw S², and a milled wheel, secured at one end of the retarding member, affords means for adjusting the latter.

It will be observed, upon reference to Fig. 2 of the drawings that the outer end of the tapering aperture or duct J, receives a conical shaped packing or gland J², which is centrally apertured for the reception of the contracted cylindrical end of the retarding member.

A washer J³ is mounted upon the retarding member, and a coiled spring J⁴ bears between said washer and another washer J⁵ upon the retarding member. The washer J⁵ is held by the spring J⁴ against a shoulder at the end of the threaded portion of the shank of the resistance member, the spring J⁴ serving to compress said packing member and hold same to its seat.

Leading through the wall of the casing is a duct T, which is in communication with a port T' formed in the bushing J', and which port T' communicates with the longitudinal duct J therein.

In the drawings I have illustrated the usual float mechanism for regulating the flow of the fuel, the float chamber being designated by letter W, and W' the float therein, a suitable valve W², pivoted to the float, being adapted to regulate the flow of the fuel from the duct X to the interior of the float chamber. It will be understood however, that the float and chamber may be dispensed with if desired, and the fuel pipe connected direct to the duct S when it is desired to introduce the fuel in any other manner.

Projecting from the inner wall of the casing are the ribs Y, shown in Figs. 2 and 3 of the drawings, and which serve to guide the resistance block as it moves back and forth.

In operation, when the parts are assembled as shown and connected to a combustion chamber, the movement of the lever, which may be operated through suitable connections convenient to the operator, away

from the valve, will cause the resistance block to move in the opposite direction and against the tension of the spring R, thus allowing the lighter spring R', which normally is under tension to expand and move the piston stem longitudinally and unseat the valve. As the resistance block is moved toward the valve the retarding member is also moved therewith and tends to restrict the flow of the fuel through the fuel duct, it being understood that the greater the suction through the valve controlled end of the Venturi passageway, the more the resistance will be to the flow of the fuel, incident to the forward movement of the retarding member within the tapering duct of the bushing. This provision is made to guard against feeding an oversupply of fuel.

It will be noted upon reference to Fig. 1 of the drawings that the action of the valve I, relative to the tapering portion of the wall B² of the coupling member B, will cause a variation in the diameter of the passageway through which the fuel and air pass to the combustion chamber and that, the farther the valve is moved away from its seat, through the medium of the lever P, the volume of the inrushing air will be maintained at a nearly uniform velocity, the varying speed of the air which is drawn through, incident to the vacuum formed within the engine, will vary according to the suction and the capacity of the passageway, the greater the suction as the valve leaves its seat, the greater will be the speed of the air and a consequent accelerating movement will be imparted to the fuel, the passageway through which the fuel passes being constricted as the valve moves from its seat. By this provision in the controller, the vacuum stage intermediate the valve and the engine will be constantly maintained while the engine is in operation and the fuel will consequently be thoroughly atomized before reaching the combustion chamber.

In the event of an engine with which the controller is equipped, going down an incline, when the valve is seated and the supply of fuel thereby cut off, any vacuum force which may be created within the engine when in operation will cause the disk valve to be drawn away from the valve I under the tension of the spring I³ and air for cooling the engine will be drawn through the apertures I⁶ and allowed to pass to the combustion chamber of the engine.

By the mechanism shown, there will be no spring resistance at any time, the incoming air or fuel and in the event of there being a back fire, the valve will quickly seat independent of the resistance block. When the valve is seated the oil supply will be sealed.

By the provision of a hinged side to the casing, a convenient means is afforded whereby access may be had to the interior

thereof for adjusting the retarding member.

What I claim to be new is:

1. An apparatus for controlling the flow of air and fuel to internal combustion engines, etc., comprising a chambered casing with an air passageway leading therefrom and a fuel duct through the wall of the latter, a valve regulating said passageway, opposing springs, one normally holding the valve seated when at rest and sealing the flow of air and fuel, means for relieving the valve from the action of its closing spring to allow the other spring to expand and unseat the valve, and means for retarding the flow of fuel as the valve unseats, as set forth.

2. An apparatus for controlling the flow of air and fuel to internal combustion engines, etc., comprising a chambered casing with an air passageway leading therefrom and a fuel duct through the wall of the latter, a valve regulating said passageway, opposing springs, one normally holding the valve seated while at rest and sealing the flow of fuel, manually operated means for relieving the valve from the action of its closing spring to allow the other spring to unseat the valve, and means for retarding the flow of fuel as the valve unseats, as set forth.

3. An apparatus for controlling the flow of air and fuel to internal combustion engines, etc., comprising a chambered casing with a passageway leading therefrom, a portion of the wall of the latter forming a valve seat with an oil duct leading therethrough, said casing having a chambered portion, the inner surface of which flares at an angle to said valve seat, a valve, a spring normally holding the valve seated to seal the flow of air and fuel when at rest and means for moving the valve which cooperates with the flaring surface of said chamber to maintain a substantially uniform flow of air and fuel as the valve moves toward or away from its seat, as set forth.

4. An apparatus for controlling the flow of air and fuel to internal combustion engines, etc., comprising a chambered casing with a passageway leading therefrom, a portion of the wall of the latter forming a valve seat with an oil duct leading therethrough, a valve, springs, one normally holding the valve seated when at rest to seal the flow of fuel through said passageway, means for relieving the valve from the action of its seating spring to allow the other spring to expand to unseat the valve, fuel-regulating mechanism, said valve being arranged to seat automatically under back fire and independent of the means employed for relieving the valve of said seating spring, as set forth.

5. An apparatus for controlling the flow of air and fuel to internal combustion en-

gines, comprising a casing which is chambered with an air passageway leading therefrom, a valve regulating said passageway, opposing springs, one serving to seat the 5 valve, and the other tending to unseat the latter, a resistance block against which the valve seating spring bears, lever means for moving said block to vary the tension of the spring which bears against same, a fuel retarding device adjustably mounted upon a 10 projection of the resistance block.

6. An apparatus for controlling the flow of air and fuel to internal combustion engines, comprising a casing which is chambered with an air passageway leading therefrom, the wall of the casing being apertured for the admission of air, a valve regulating the exit of said passageway, opposing springs, one serving to seat said valve and 15 the other tending to unseat the latter, a resistance block against which the valve seating spring bears, rack teeth upon a projection of said block, a lever with teeth engaging said rack teeth, and a fuel retarding device fixed to the block.

7. An apparatus for controlling the flow of air and fuel to internal combustion engines, comprising a casing which is chambered with an air passageway leading therefrom, a valve regulating said passageway, opposing springs, one serving to seat the valve, and the other tending to unseat it, a resistance block against which the valve seating spring bears, rack teeth formed upon 30 a projection of said block, a pivotal lever having teeth in mesh with said rack teeth, a fuel retarding device, having a threaded circumference adjustably held in a projection of said resistance block, and regulating the 35 feeding of the fuel to be mixed with air.

8. An apparatus for controlling the flow of air and fuel to internal combustion engines, comprising a casing which is chambered with an air passageway leading therefrom, a valve regulating said passageway, opposing springs, one serving to seat the valve, and the other tending to unseat it, a stem to said valve mounted to move back and forth in suitable bearings, a resistance 45 block movable upon said stem and against which block the valve seating spring is adapted to bear, a lever for moving said block, a fuel retarding device carried by said block and means for adjusting said retarding device.

9. An apparatus for controlling the flow of air and fuel to internal combustion engines, comprising a casing which is chambered with an air passageway leading therefrom, a valve regulating the flow of air and fuel through said passageway, a stem to said valve, a resistance block movably mounted upon said stem, a spring bearing between 60 said block and casing and serving to seat the

valve, a collar fixed to the stem, a second spring bearing against said collar, said resistance block being normally held against the collar by the tension of the valve seating spring, lever mechanism for actuating the block, and a fuel retarding device carried by 70 the resistance block.

10. An apparatus for controlling the flow of air and fuel to internal combustion engines, comprising a casing which is chambered with an air passageway leading therefrom, a valve regulating said passageway, a stem to the valve, a resistance movably mounted upon said stem a spring bearing between the casing and said block, a collar fixed to the stem, a second spring bearing 75 between one end of the casing and said block, means for actuating the resistance block, a projection of the latter having a split portion with threaded recesses therein, a fuel retarding member having a circumferentially threaded part engaged by the walls of said threaded recesses, a bushing communicating with an oil duct, and in which bushing one end of the retarding member 80 has a play.

11. In an apparatus for controlling the flow of air and fuel to internal combustion engines, the combination with a casing which is chambered with an air passageway leading therefrom, a spring actuated valve controlling said passageway, a fuel bushing mounted in the casing and communicating with an oil duct therein which leads through the seat of said valve, said bushing having a tapering duct therein a fuel port leading 90 to the latter, a packing in the end of said duct of the bushing, a retarding member having a cylindrical end movable through said packing and into said tapering duct, a spring bearing against said packing, and 95 means for moving said retarding member synchronously with the regulation of said valve.

12. An apparatus for controlling the flow of air and fuel to internal combustion engines comprising a casing with a chambered portion having an air passageway, a valve seat in the wall of the latter, a valve adapted to contact with said seat, opposing springs, one normally holding the valve seat and sealing the flow of fuel and air and the other tending to unseat the valve, means for 110 varying the tension of the valve closing spring to allow the valve to unseat, a coupling member having a chambered portion, 115 the wall of which adjacent to the valve seat is tapering, affording means whereby, as the valve unseats, the space intermediate the circumference of the valve and said inclined surface will increase, as set forth.

13. An apparatus for controlling the flow of air and fuel to internal combustion engines comprising a casing with a chambered

portion having an air passageway, a valve seat in the wall of the latter, a valve adapted to contact with said seat, opposing springs, one normally holding the valve seat and sealing the flow of fuel and air and the other tending to unseat the valve, means for varying the tension of the valve closing spring to allow the valve to unseat, a coupling member fastened to said casing and having a chambered portion, the wall of which adjacent to the casing is tapering and at an angle to the valve seat, as set forth.

14. An apparatus for controlling the flow of air and fuel to internal combustion engines, comprising a casing with a chambered portion having an air passageway, an apertured valve regulating said passageway, opposing springs, one normally holding the valve seated and sealing the flow of fuel and the other tending to unseat the valve, means for varying the tension of the valve closing spring and allowing the valve to unseat, and a spring-pressed disk valve mounted upon

said valve and normally closing the apertures in the valve, as set forth. 25

15. An apparatus for controlling the flow of air and fuel to internal combustion engines, comprising a casing which is chambered and provided with an air passageway, an apertured valve regulating said passageway, opposing springs, one normally holding the valve seated and sealing the flow of fuel and the other tending to unseat the valve, means for varying the tension of the valve closing spring and allowing the valve 30 to unseat, a disk valve in contact with said apertured valve, a screw fitted to the valve, and a spring interposed between the head of the screw and the disk valve, as set forth.

In testimony whereof I hereunto affix my 35 signature in the presence of two witnesses.

EDWARD G. SHORTT.
